COMBINED CALENDAR AND NAME PLATE

Max Tucker, Waterloo, Iowa, assignor to Waterloo Idea Companies, doing business as King Midas Products, Waterloo, Iowa, a corporation of Iowa

Filed Oct. 19, 1964, Ser. No. 82,261

Term of patent 14 years

(Cl. D74—5)

FIG. 1

FIG. 2

FIG. 3

FIG. 4FIG. 5FIG. 1 is a front view showing the new design for a combined calendar and name plate,

FIG. 2 is a back view thereof with the lettering for illustration only,

FIG. 3 is an end view thereof,

FIG. 4 is a top view thereof, and

FIG. 5 is a bottom view thereof.

I claim:

The ornamental design for a combined calendar and name plate, as shown.

The essential features of the design reside in the portions shown in solid lines.
